J. E. MAYNARD

FOOTBALL

Filed Oct. 11, 1923

Inventor:
John E. Maynard,
By Meador, Calvert, Copeland and Dine,
Attorneys.

UNITED STATES PATENT OFFICE.

JOHN E. MAYNARD, OF PLYMOUTH, NEW HAMPSHIRE, ASSIGNOR TO THE DRAPER-MAYNARD COMPANY, OF PLYMOUTH, NEW HAMPSHIRE, A CORPORATION OF NEW HAMPSHIRE.

FOOTBALL.

Application filed October 11, 1923. Serial No. 667,984.

To all whom it may concern:

Be it known that I, JOHN E. MAYNARD, a citizen of the United States, residing at Plymouth, county of Grafton, State of New Hampshire, have invented a certain new and useful Improvement in Footballs, of which the following is a specification, reference being had therein to the accompanying drawings.

10 This invention has for its object to provide a football especially adapted for use in playing the present open game wherein the ball is frequently thrown by hand in the play known as the "forward pass". In 15 the execution of this play, it is necessary that the ball be grasped by the end and quickly and accurately thrown, and in wet weather, when the ball is slippery, it is difficult to obtain a sufficiently firm grip 20 thereon to accomplish this successfully. In accordance with the present invention, a football of conventional form is provided at each end with a series of roughened, circumferentially extending lines, preferably 25 formed by stitching, whereby the player is enabled to grip the ball firmly without danger of slipping.

The invention will best be understood from the following description of one form 30 or embodiment thereof illustrated in the accompanying drawings, in which:

Fig. 1 is a plan view and Fig. 2 an end elevation.

The football shown is of the usual generally ellipsoidal form and comprises four longitudinal sections or lenticular gores 10, preferably of pigskin or other suitable

leather, sewed together at their edges along longitudinal seams 11 one of which is interrupted intermediate its ends to provide 40 an opening 12 for the insertion of the usual inflating bladder 13, which opening is closed by lacings 14.

In accordance with the present invention, each section 10 is provided adjacent each 45 end with transverse roughened lines preferably formed by seams of relatively coarse stitching 15. The lines of stitching 15 are preferably correspondingly located on the several sections, so as to constitute continuations of each other and form continuous circumferential lines on the completed football at the ends of the latter, and extending thereabout in a direction transverse to its major axis, thereby rendering the ball easy 50 to grasp and enabling the same to be securely held and accurately thrown even when wet.

Having thus described my invention, I 60 claim:

A football of generally ellipsoidal form comprising a plurality of longitudinal sections sewed together at their edges to form longitudinal seams, one of said seams having a central opening for the reception of an 65 inflatable bladder, and a series of spaced circumferential lines of stitching disposed transversely to said seams at the opposite ends of said ball, said series extending from the ends of said central opening to points 70 adjacent the extreme opposite ends of said ball.

In testimony whereof I affix my signature.
JOHN E. MAYNARD.
